UNITED STATES PATENT OFFICE.

WILLIAM H. EMOND, OF BOSTON, MASSACHUSETTS, ASSIGNOR TO THE
EMOND GEARING COMPANY, OF SAME PLACE.

DESIGN FOR A REAR AXLE FOR WAGONS OR CARRIAGES.

SPECIFICATION forming part of Design No. 32,703, dated May 22, 1900.

Application filed March 19, 1900. Serial No. 9,343. Term of patent 7 years.

To all whom it may concern:

Be it known that I, WILLIAM H. EMOND, a resident of Boston, in the county of Suffolk and State of Massachusetts, have invented and 5 produced a new and original Design for Rear Axles for Wagons or Carriages, of which the following is a specification, reference being had to the accompanying drawings.

Figure 1 shows a perspective of a rear axle 10 of my design. Fig. 2 shows a plan view. Fig. 3 shows a cross-section taken on line A B of Fig. 2 and the parts to the left of the section-line.

The feature of the invention is the form or 15 configuration of the rear axle, as shown—that is to say, having the body portion 1, the lateral projections 2 2, substantially of the form

and relative size to the body, as shown, and arranged substantially as shown, and the raised central portion 3, having keyhole-like 20 openings, substantially as shown.

Having described my invention, what I claim as new, and desire to secure by Letters Patent, is—

The design for a rear axle for carriages and 25 wagons, substantially as herein shown and described.

In testimony whereof I have hereunto set my hand to this specification, in the presence of two witnesses, this 3d day of March, 1900. 30

WILLIAM H. EMOND.

Witnesses:

HUGH G. BROWN,
JAMES BROWN.
